ROBERT FARIES, OF ST. DAVIDS, PENNSYLVANIA

RAILWAY TRACK

Application filed January 23, 1930. Serial No. 422,932.

Where the rails of a railway track abut they are held in alignment by jointbars (sometimes termed "fish plates") bolted to the webs of the rails. Under track usage the 5 contacting surfaces of the rails and jointbars wear, and in order to maintain rigidity of the structure it is necessary periodically to tighten the nuts on the bolts which unite the rails and jointbars, an operation which is resisted by the rusting of the thread of the bolt 10 and freezing of the nut in place.

The intervals at which the bolts require to be tightened can be lengthened, the tightening operation facilitated, and the track rendered more rigid and noiseless by maintaining oil on the contacting surfaces of rail and jointbar and upon the threaded end of the bolt upon which the nut must be tightened. Efforts have been made to effect this by the 20 injection of oil into the space between the jointbars and the rails, but so far as I am aware these efforts have failed, either because the oil so injected has been so fluid as to run out of place and disappear in a short time, 25 or else where efforts have been made to retain the oil in place by means of a fabric an opposite condition has prevailed, the fabric after parting with some of the oil holding the remainder so tenaciously on the inside of 30 the jointbar as to prevent its disseminating itself.

I have discovered a way of distributing and maintaining oil upon these surfaces for a long period of time which I will now describe.

35 In order to keep the oil in place it has heretofore been proposed to incorporate it with a fabric such as a felt or a textile or a mass of cotton waste. These materials are so absorbent and they hold most of the oil so tenaciously that there is prevented that slow and continued dissemination which alone accomplishes the desired end. I have discovered that the proper oiling of the rail joints can be 40 accomplished by mixing the oil with a proper vehicle consisting of finely comminuted vegetable matter, such as wood flour. This is not gritty as a mineral vehicle would be. And while a fibrous fabric remains in place indefinitely and holds back the oil, the comminuted

matter flows with the oil and permits its gradual and continued dissemination.

Railroads reclaim their waste oil by re-distillation. This re-distillation leaves a residuum or sludge oil of little or no value. 55

I mix this sludge oil with a sufficient quantity of wood flour to produce an oily compound from which oil will not too readily flow but which when placed between the rail and jointbar will form itself into a mass of 60 such consistency as to slowly flow and disseminate itself for a long time.

The accomplishment of the desired result depends upon the proper admixture of the oil with the wood flour, and this in turn depends upon the viscosity of the oil produced as a residuum of the distillation of which I have spoken, it being necessary to add enough of the wood flour to attain in the admixture a proper degree of consistency. 70

An example of the practice of my invention as applied to jointbars of a standard construction is illustrated in the accompanying drawings, whereof:

Fig. I is a plan view of a jointbar filled with a packing comprising the above described mixture, a part of one of the rails being broken away for convenience in illustration; and 75

Fig. II is a cross section of the same taken along the lines II—II of Fig. I.

In the accompanying drawings 1 is a rail. 2, 2 are the jointbars. 3 is the bolt passing through a slot in the web of the rail, and 4 is the bolt nut. The hole for the bolt at its head end is non-circular preventing rotation. The hole for the threaded end of the bolt is unthreaded leaving a spiral passage extending to the face of the nut 4. The interspace between the web of the rail and the jointbars is 80 filled with a mass 5 of the material just described.

I will describe two methods of application.

First I inject this oily material 5 into the space between the rails and their connecting jointbars. This injection is best accomplished by means of a device which injects the material simultaneously at both ends of the interspace between the rail and the jointbar under pressure. For this purpose the 100

material used must be of a sufficiently fluid consistency to enable it to be handled in the manner I have described. I have found that by mixing say about 88 lbs. of wood flour with 12 lbs. of residuum there is produced a mixture well adapted to my purpose but the proportions may vary according to the consistency of the materials so long as the result is a mixture which is sufficiently fluid or 10 viscous to be handled in the way I have described, but not more fluid than is necessary. Under these conditions the material settles in its position between the jointbars and the rails and does not lose its oil while 15 yet slowly exuding and distributing itself along the adjacent surfaces and through the bolt holes or thread spaces of the bolts to the outside of the jointbar. In this way there is obtained a permanent lubrication of the contacting 20 surfaces of the jointbar and rail. The oily mixture also travels along the bolt and lubricates the threaded surface upon which the nut must be tightened.

Second. Another method of accomplishing my result is to produce a mixture of the same materials of a somewhat greater consistency, or plasticity for which the proportion of wood flour must be increased. In this way I obtain a homogeneous combination of 25 residuum and wood flour in a plastic condition capable of being molded into a flat cake of suitable shape which is applied to the web of the rails at the joints and covered by the jointbar when put in place, the bolt being 30 run directly through it. This material similarly slowly exudes and disseminates itself.

My procedure accomplishes several desirable results. It facilitates the tightening operation by rendering easy the screwing up 40 of the nut. The lubrication and the packing of the interspaces between the rails and jointbars renders the track more noiseless under usage. The wear of both rail and jointbar is lessened. The ultimate freezing up of 45 the track joints which prevents expansion and contraction of the rails is overcome.

Other available oil than that which I have mentioned may be used, and other comminuted vegetable fiber than wood flour may 50 fill the requirements provided that when combined with the oil it produces an oily substance which slowly disseminates itself and yet which has sufficient consistency to make possible its application to or injection into 55 the interspace between the jointbar and the rail.

Having thus described my invention, I claim:

1. In a rail joint, the combination with adjacent rails, an overlapping joint bar, and bolts securing the joint bar to the rails, of a self-disseminating lubricant mass in the space between joint bar and rail ends, consisting of oil mixed and combined with a retentive 60 but fluent finely divided vehicle, which flows

with the oil along the adjacent surfaces and through the bolt holes and thread spaces, thus permanently lubricating the joint.

2. In a rail joint, the combination with adjacent rails, an overlapping joint bar, and bolts securing the joint bar to the rails, of a self-disseminating lubricant mass in the space between the joint bar and rail ends, consisting of oil residuum mixed and combined with comminuted vegetable matter of such fineness and in such proportions that while the oil is retained in the joint by the vegetable matter, yet the latter flows and distributes itself throughout the joint along with the oil.

3. In a rail joint, the combination with adjacent rails, an overlapping joint bar, and bolts securing the joint bar to the rails, of a self-disseminating lubricant mass in the space between joint bar and rail ends, consisting of oil mixed and combined with wood flour in such proportions that while remaining in the joint the compound automatically flows and disseminates itself through the interstices and lubricates the joint.

In testimony whereof, I have hereunto signed my name at Philadelphia, Pennsylvania, this 20th day of January, 1930.

ROBERT FARIES.
